(57) CLAIM

The ornamental design for a top portion of a spring core, as shown and described.

DESCRIPTION

FIG. 1 is a top plan view of a top portion of a spring core showing our design;

FIG. 2 is an enlarged fragmentary view taken from the bottom left corner of FIG. 1;

FIG. 3 is a side elevational view;

FIG. 4 is an enlarged fragmentary view taken from the far left in FIG. 3;

FIG. 5 is a side elevational view, showing the side opposite that shown in FIG. 3;

FIG. 6 is an enlarged fragmentary view taken from the far left in FIG. 5; and

FIG. 7 is an end elevational view;

FIG. 8 is an enlarged fragmentary view taken from the far left in FIG. 7;

FIG. 9 is an end elevational view showing the end opposite that shown in FIG. 7; and,

FIG. 10 is an enlarged fragmentary view taken from the far right in FIG. 9.

The broken lines are for environmental purposes only and form no part of the claimed design.
